PERMANENT BOWKNOT

Michael Lewis, Detroit, Mich.

Application July 22, 1943, Serial No. 495,757

3 Claims. (Cl. 2-151)

My invention relates to neckties, and has among its objects and advantages the provision of an improved permanent bowknot.

In the accompanying drawing:

Figure 1 is a front view of a bowknot in accordance with my invention.

Figure 2 is a rear view.

Figure 3 is a top edge view.

Figure 4 is a sectional view along the line 4-4 of Figure 2.

Figure 5 is a perspective view of a knot form, and

Figure 6 is a perspective view of a tensioning spring.

In the embodiment of the invention selected for illustration, I make use of a rubber bow form or core 10 having a straight upper edge 12, right angular end edges 14 and angular bottom edges 16 coacting with the short bottom edge 18 and the end edges 14 to provide pointed wings 20. A suitable tie cloth 22 covers all surfaces of the form.

A band or loop 24 of a width equalling the length of the edge 18 is looped about the cloth covered form to simulate a part of the bowknot 26 and serves as a connection for the neck strap 28, which strap is passed through the loop adjacent the rear face of the bowknot. One end of the strap 28 is provided with a ring 30 into which a hook 32 attached to the other end of the strap is engaged, the strap being elastic and provided with a conventional adjustment 34.

The form 10 is provided with a slot 36 paralleling the edge 12. This slot is located close to the edge 12 so that the upper bar 38 is somewhat more flexible than the bottom bar 30. The cloth 22 is so tensioned as not to alter the contour of the form 10. Thus the loop 24 may be so tensioned as to impart a slight bend to the bar 38 and thereby impart slack to the cloth 22, which slack folds inwardly of the slot to provide a wrinkle 42 enhancing the pleasing appearance of the bow 26.

A flat spring 44 is inserted between the bow

26 and the strap 28, which spring is normally straight and provided with rolled ends 46 engaging the cloth 22. The loop 24 is drawn sufficiently tight to flex the body of the spring against the cloth covered form 10, so that the spring will press the strap 28 against the loop 24 and prevent accidental displacement of the bow 26 on the strap 28.

Without further elaboration, the foregoing will so fully explain my invention, that others may, by applying current knowledge, readily adapt the same for use under various conditions of service.

I claim:

15 1. A tie comprising a resilient bow form of flexible material having a slot therein to provide a relatively stiff lower bar and a relatively flexible upper bar, a tie material covering said form, a loop extending about the material covered tie and flexing the upper bar to buckle said material inwardly of the slot, a neck strap threaded through said loop, and a spring means interposed between the material covered form and said neck strap and flexed by said loop to frictionally connect the neck strap and said loop.

20 2. A tie comprising a resilient form of flexible material provided with an elongated slot adjacent one edge to provide a relatively stiff lower bar and a relatively flexible upper bar, tie material covering the form, and a loop of material extending above the material covered tie and flexing the upper bar to buckle said material inwardly of the slot to provide a wrinkled effect, and a neck strap extending through the loop.

25 3. A tie comprising a resilient form of flexible material provided with an elongated slot adjacent one edge to provide a relatively stiff lower bar and a relatively flexible upper bar, tie material covering the form, a loop of material extending above the material covered tie and flexing the upper bar to buckle said material upwardly of the slot to provide a wrinkled effect, and a neck strap carried by the rear face of the tie.

MICHAEL LEWIS.
